THOMAS J. JACKSON, OF REYNOLDSBURG, OHIO.

UNITED STATES PATENT OFFICE.

SEED-PLANTER.

SPECIFICATION forming part of Letters Patent No. 290,887, dated
Application filed May 31, 1893. (No model.)

Witnesse: THOMAS J. JACKSON.
A. C. OSBORN,
E. S. OSBORN.
Presence of two witnesse.

to which he has referred, the author of the article, A. C. Osborn, in his article, "The Art of Invention," in the *Harvard Business Review*, says: "The first step in the process of invention is to define the problem. The second step is to collect all the facts and figures that are available. The third step is to analyze the problem and to determine the best way to solve it. The fourth step is to invent a solution. The fifth step is to test the solution and to make any necessary changes. The sixth step is to put the solution into practice. The seventh step is to evaluate the results and to make any necessary improvements. The eighth step is to repeat the process if necessary." In fact, in its general features it is similar to the process of invention, but it is more detailed and more specific.
